UNITED STATES PATENT OFFICE.

ROBERT S. ALLYN, OF NEW YORK, N. Y.

CAN-CLOSURE.

No. 826,215.

Specification of Letters Patent.

Patented July 17, 1906.

Application filed December 2, 1905. Serial No. 289,947.

To all whom it may concern:

Be it known that I, ROBERT S. ALLYN, a citizen of the United States, residing at New York, county of Kings, State of New York, have invented certain new and useful Improvements in Can-Closures, of which the following is a full, clear, and exact description.

My invention relates to cans, and particularly to friction-closures.

10 The object is to provide a can particularly adapted for safely retaining, shipping, and dispensing fluids which can be manufactured at reasonable cost and which may be opened and closed repeatedly.

15 I am aware that many so-called "friction-top" cans have been heretofore proposed and that some of them have gone extensively into use.

20 In its preferred form it consists in a can having an annular top and a removable cover. The top has a horizontally - positioned main ring portion with a ledge at the outer edge and an elastic vertically-positioned slightly-tapering flange portion at the 25 inner edge forming a friction-seat wall which has an inclined annular shoulder. The cover has a main horizontal disk-like central portion with a projecting rim and an elastic vertically - positioned slightly-tapering flange 30 portion at its edge forming a friction-seat wall which has an inclined annular shoulder. The parts are so positioned and proportioned that when the cover is pushed down in place the friction-seat walls fit snugly together and 35 the inclined shoulder of the cover snaps under the inclined shoulder of the top, the elastic or springy quality of the parts tending to draw or force the cover down more firmly in place, the disk portion of the cover being adjacent the edge of the top flange.

40 The drawings illustrate several forms of cans of my invention, and the rights to apply for and obtain patents for the forms not specifically claimed herein are reserved for other applications.

45 The parts are constructed of sheet metal—for instance, tin—and require no packing of joints other than the friction and locking joints provided by the top and cover.

50 The figures are all fragmentary sectional views of can bodies, tops, and covers, with the metal much heavier than in ordinary practice.

55 Figure 1 shows the preferred form which is specifically claimed in this application. In Fig. 1, 1 is the body, 2 is the top, and 3 is the

cover. The top and body may be integral, but are preferably made of separate parts soldered together. The top has a ledge 4, ring 5, friction-seat wall 6, and shoulder 7. 60 The cover has a rim 8, friction-seat wall 9, upturned edge 10, and shoulder 11. The shoulder 7 snaps into the groove between the disk part 3 of the cover and the shoulder 11, drawing the cover down and making a wedge-like joint against 3. The edge 10 may be omitted. In this form the cover is protected from injury, is held very tightly in place, but may be readily pried off.

65 Fig. 2 shows a form similar to Fig. 1, but the edge 10' forms a friction-wall engaging the wall 5' of the top ring and affords an additional seat.

70 In Fig. 3 the slightly-tapering elastic friction-seat wall 13 of the top terminates in an outwardly-turned inclined shoulder 14, preferably preceded by the slightly inwardly curved groove 15. The friction-seat wall 17 of the cover has a groove 19, forming an inclined shoulder 20, on which the shoulder 14 75 snaps as the cover is pushed down, the edge of the disk part 16 being adjacent the free edge 14 of the top, so as to afford considerable resistance to the expansive force. The ledge 18 is also near the rim 12. This can 80 has a large capacity.

85 Fig. 4 shows a form similar to Fig. 3; but the groove 15' is at the bottom of the friction-seat 13 of the top and forms the inclined shoulder 14'. The inclined shoulder 20' 90 snaps under the shoulder 14'. This can does not require quite as much accuracy of construction.

95 In Fig. 5 the friction-seat 24 of the depressed top 23 terminates in a spring-flange 95 with an inwardly-projecting inclined shoulder 25 and an outwardly-turned free edge 26. The friction-seat 28 of the cover has an exterior groove 29, forming the shoulder 30. The inclined spring-shoulder 25 presses down 100 on the inclined shoulder 30 of the cover and tends to draw the cover into closer contact with its seat, as well as affording a sharp line of contact. The ledge 22 and rim 27 are close together. The disk part 21 is adjacent 105 the free edge 26. This can be made cheaply, and the top drains well into the can.

110 Fig. 6 shows a form similar to Fig. 5; but the inclined shoulder 30' of the cover snaps into the grooves 25' in the top ring, and the shoulder 26' makes another joint beneath the cover-disk 21.

In Fig. 7 the friction-seat wall 33 of the top ring has the shoulder 34. The cover-seat wall has the outwardly-turned flange-shoulder 38 to snap under the shoulder 34. The rim 36 of the cover-disk 35 is adjacent the ledge 32 for prying purposes. This can be made cheaply and has a large capacity.

Fig. 8 shows a form similar to Fig. 7; but the shoulder 34' is of less diameter than the friction-seat 33. The wall 37 has the groove 38' to form the shoulder 39', which snaps under the shoulder 34'. This cover may be put on easier than the cover of Fig. 7.

Each form has its own advantages, either in cost or ease of construction, capacity, efficiency of joint, ease of opening or ease of closing, or durability, which makes each form desirable in particular cases.

What I claim is—

- 20 1. A friction-top comprising a body, a sheet-metal top ring having a wall affording a substantial friction-seat and an annular outwardly-turned flanged locking-shoulder, and a removable sheet-metal cover having a wall affording a substantial friction-seat, an exteriorly-projecting rim and an annular interior groove, said shoulder being adapted to snap into said groove for drawing and holding said cover down snugly on its seat.
- 25 2. A friction-top comprising a body, a sheet-metal top ring having a wall affording a substantial seat and an annular locking-shoulder, and a removable sheet-metal cover having a wall affording a friction-seat and an annular shoulder beneath the under side of the top, said top shoulder being adapted to snap over said cover-shoulder and wedge beneath the top for forming two tight joints in addition to the friction-seat engagement.
- 30 3. A friction-top comprising a body, a sheet-metal top ring having a downwardly-turned wall with an upwardly-turned extension affording a friction-seat terminating in an outwardly-turned elastic shoulder, and a removable cover having a friction-seat, an exterior rim and an interior shoulder over which said elastic shoulder is adapted to snap when said seats are in engagement.
- 35 4. A friction-top comprising a body, a yielding sheet-metal top ring having a ledge, a wall affording a friction-seat of substantial area and an annular locking-shoulder, and a removable yielding sheet-metal cover having

a rim adjacent the ledge of the top ring, a wall affording a friction-seat, and an annular groove into which said shoulder is adapted to snap.

5. A friction-top comprising a body, a sheet-metal top ring having a slightly-tapering friction-seat wall terminating in an annular outwardly-flaring elastic shoulder, and a removable cover having a slightly-tapering friction-seat wall and a shoulder adapted to be engaged by said top shoulder.

6. A friction-top can-closure comprising a top having a ledge, an upturned elastic friction-seat wall terminating in an outwardly-turned shoulder, and a removable cover having an interior groove for the shoulder, a downturned friction-seat wall and a projecting rim adjacent the top ledge when the cover is in place.

7. A can-closure comprising the combination with a top member having a ledge, an annular horizontally-positioned ring and an elastic vertically-positioned slightly-tapering friction-seat wall, with a continuous inclined locking-shoulder, of a cover member having a central disk-like portion, a projecting rim, and an elastic vertically-positioned slightly-tapering friction-seat wall with a continuous inclined locking-shoulder, the parts being so positioned and proportioned that the shoulders interlock and the elastic quality of the parts draws the friction-seat walls into closer engagement with each other the disk-like central portion of the cover being adjacent the free edge of the top flange when the shoulders are interlocked.

8. A friction-top can-closure comprising a body, a top ring having a ledge and a downwardly-turned flange with an upwardly-turned extension forming a friction-seat wall and terminating in a locking-shoulder and a removable cover having a projecting rim, a locking-groove for said shoulder and a downwardly-turned flange forming a friction-seat wall adapted to engage the upwardly-turned extension-wall of the top ring, said cover being free from contact with the downturned flange of said top ring.

ROBERT S. ALLYN.
